FIG. 2.

FIG. I.

INVENTOR:
George W. Osborn
By Ray D. Lehr
ATTORNEY

UNITED STATES PATENT OFFICE

GEORGE W. OSBORN, OF CLEVELAND, OHIO, ASSIGNOR TO THE RELIANCE GAUGE COLUMN COMPANY, OF CLEVELAND, OHIO, A CORPORATION OF OHIO

GAUGE COCK

Application filed November 6, 1931. Serial No. 573,420.

This invention relates to valve actuating devices and my invention, while applicable in its broader aspects to various kinds of valves, is especially useful as applied to the 5 gauge cocks of water columns of steam boilers and I shall describe and explain the invention in connection with this latter application.

Steam boiler water columns, in addition to 10 having the usual glass water gauge for giving visual indication of the water level in the boiler, are usually fitted with a plurality of gauge cocks opening into the column at different levels. Usually three such gauge 15 cocks are provided and by opening these cocks one after another, beginning with the top one, the boiler attendant can secure a rough indication of the water level. The gauge cocks are especially useful in case the glass 20 water gauge is temporarily put out of commission by breakage.

The gauge cocks referred to are commonly provided with actuating devices by means of which the boiler attendant can conveniently 25 open and close the valves while standing on the boiler room floor, a common practice being to provide each gauge cock with an operating lever and a pull chain attached to the lever and depending therefrom to be conveniently 30 grasped by the attendant. It is necessary to mount the gauge cocks close enough to each other so that there is a tendency for interference between adjacent operating levers, especially if levers of the weighted 35 type are employed; and as a result with prior forms of construction known to me there has been a tendency for the valve lever moved by the attendant to strike the lever of an adjacent valve and cause the opening of the latter with resultant confusion to the attendant.

One of the objects of the present invention is the provision of an improved form of valve-actuating device which is adapted, when such devices are mounted on a plurality 45 of associated valves, to prevent the difficulty above referred to.

More specifically, it is an object of the invention to provide a valve-actuating device so formed that a portion of said device, when 50 its valve is moved to open position, shall en-

gage a different portion of a similar actuating device of the next adjacent valve to hold the latter valve closed, and preferably also to limit the opening movement of the valve primarily actuated.

Other objects of the invention more or less ancillary or incidental to the objects above stated, as well as the manner of attaining the various objects, will be apparent from the following description of a preferred embodiment of the invention as applied to water column gauges.

In the drawing, Fig. 1 is an elevation of the main part of a water column with my improved form of gauge cocks mounted 60 thereon.

Fig. 2 is a sectional view of the bottom gauge cock and a portion of the wall of the water column.

Fig. 3 is a plan view of one of the gauge 70 cock actuating levers.

Fig. 4 is a side elevation of said lever.

Referring in detail to the construction illustrated, 1 designates the main part of a water column adapted to be connected with a steam 75 boiler in the usual and well known manner. This water column is adapted to carry the usual glass water gauge which, however, is not shown as it constitutes no part of my present invention. The side wall of the water 80 column 1 is drilled and tapped with a series of three holes as at 1^a to receive a corresponding number of gauge cocks each of which is designated in its entirety by the numeral 2. In the form of construction illustrated, each 85 gauge cock comprises a body or casing part 3, the inlet end of which is provided with a threaded nipple 3^a to fit one of the openings 1^a. The casing 3 is also formed with a discharge nozzle 3^b. The passage through the casing is controlled by a valve 4 which has its stem threaded at 4^a to engage the correspondingly internally threaded boss 3^c of the casing. The valve 4 is arranged to cooperate with a valve seat 3^d to close or open the passage through the casing when the valve stem is turned.

On the outer end of the valve stem is mounted my improved actuating lever 5, the said lever being formed with serrated aperture 5^a 90

which is adapted to fit the correspondingly serrated portion 4^b of the valve stem. The said stem is formed adjacent the serrated portion with a shoulder 4^c to form an abutment for one side of the lever 5 and the latter is firmly secured by a nut 6 on the end of the valve stem so that movement of the lever correspondingly rotates the valve and moves it toward or from its seat according to the direction of the rotation.

The actuating lever 5 is formed at one end with an aperture 5^b to receive a pull chain 7 which is fitted at its lower end with a handle 8 and is made of such length that the boiler attendant standing on the furnace floor can conveniently grasp the handle and pull the chain to open the gauge cock valve. The other end of the operating lever 5 is formed with an enlargement 5^c which serves as a weight to turn the valve stem in a closing direction when the attendant releases the pull chain, and to normally hold the valve in closed position. In addition, each of the actuating levers 5 is formed on its lower side with a projecting finger 5^d and on its upper side with a second projecting finger 5^e, these fingers being of suitable forms to perform the functions herein-after pointed out.

With the series of gauge cocks mounted on the water column as shown in Fig. 1, it will be seen that when the operating lever 5 of any one of the gauge cocks is moved into position by the downward pull on its chain 7, one of its fingers 5^d or 5^e, will be brought into engagement with one of the fingers of an adjacent valve lever in such a manner that a closing force is applied to the second valve while the latter and its actuating lever serve as a positive stop to limit the opening movement of the valve actuated by the attendant. In Fig. 1 the upper gauge cock is shown in closed position by the full lines and in open position by the dotted lines and it will be observed that when the upper gauge cock is in open position its finger 5^d is brought into engagement with the upper finger 5^e of the middle gauge cock in a manner to press the valve of the latter more firmly against its seat and so that the finger 5^e of the middle gauge cock serves as a positive stop to limit the opening movement of the upper gauge cock.

Similarly, when the middle gauge cock is opened its lower finger 5^d engages the upper finger 5^e of the bottom gauge cock so that the opening movement of the middle cock is positively limited and its weighted end 5^c is prevented from striking against the weighted end of the upper gauge cock and moving the valve of the latter to open position. Furthermore when the bottom finger 5^d of the middle gauge cock engages the upper finger 5^e of the bottom gauge cock, the upper finger 5^e of the middle gauge cock also engages the base portion 5^d of the upper gauge cock in a

manner to prevent opening movement of the latter.

When the bottom gauge cock is opened by the movement of its operating lever 5 from the full line position to the dotted line position shown in Fig. 1, its upper finger 5^e comes into engagement with the base portion of the lower finger 5^d of the middle gauge cock so as both to limit the opening movement of the bottom gauge cock and hold the middle gauge cock in closed position.

It will be seen that while each of the gauge cocks is a self-contained device it is adapted to co-act with the adjacent gauge cock or cocks in a manner to prevent improper opening of a cock which is not intended to be actuated. Furthermore, as the co-acting features of the gauge cocks are limited to the actuating lever a set of gauge cocks of old or prior forms of construction can be equipped to embody my invention simply by providing them with my improved form of valve actuating lever. These levers, it will be observed, are identical in form and construction and it is a simple and easy matter for a workman to mount them upon the stems of the gauge cock in suitable manner.

While I have illustrated a preferred embodiment of my invention, it will be understood that various other forms of construction may be employed to embody the invention as defined by the appended claims.

What I claim is:

1. In a valve mechanism, the combination of a plurality of valves adapted to be opened and closed one at a time in the normal operation of the mechanism; and an actuating device for each valve, the said actuating devices being formed and arranged so that the actuating devices of valves adjacent to each other mutually engage when one of the valves is opened to limit its opening movement and hold the other adjacent valve closed.

2. In a valve mechanism, the combination of a plurality of valves adapted to be opened and closed one at a time in the normal operation of the mechanism; and identical actuating devices for the several valves, said devices being formed and arranged so that the actuating devices of valves adjacent to each other mutually engage when one of the valves is opened to limit its opening movement and hold the other adjacent valve closed.

3. In a valve mechanism, the combination of a plurality of valves adapted to be opened and closed one at a time in the normal operation of the mechanism; and an actuating device for each valve, the said actuating devices being formed and arranged so that the actuating devices of valves adjacent to each other mutually engage when one of the valves is opened to afford a positive stop definitely limiting the opening movement of said valve.

4. In a valve mechanism, the combination of a plurality of valves adapted to be opened

and closed one at a time in the normal operation of the mechanism; and an actuating device for each valve, the said actuating devices being formed and arranged so that the 5 actuating devices of valves adjacent to each other mutually engage when one of the valves is opened to hold the other adjacent valve closed.

5. In a valve mechanism, the combination 10 of a plurality of valves adapted to be opened and closed one at a time in the normal operation of the mechanism; and an actuating device for each valve, the said actuating devices being formed and arranged so that 15 when one of the valves is moved to open position the opening of an adjacent valve is prevented by mutual engagement of the actuating devices of said valves.

6. In a valve mechanism for indicating the 20 water level in steam boilers, the combination of an upright water column; and a plurality of gauge cocks mounted on said column one above another, each cock comprising a valve and a lever for actuating it and the several 25 actuating levers being formed and arranged so that the levers of valves adjacent to each other mutually engage when one valve is opened to limit its opening movement and hold the other adjacent valve closed.

30 7. In a valve mechanism for indicating the water level in steam boilers, the combination of an upright water column; and a plurality of gauge cocks mounted on said column one above another, each cock comprising a valve 35 and a lever for actuating it and the several actuating levers being formed and arranged so that the levers of valves adjacent to each other mutually engage when one valve is opened to hold the other adjacent valve 40 closed.

8. In a valve mechanism for indicating the water level in steam boilers, the combination of an upright water column; and a plurality of gauge cocks mounted on said column one 45 above another, each cock comprising a valve and a lever for actuating it and the several actuating levers being identical and formed and arranged so that the levers of valves adjacent to each other mutually engage when 50 one valve is opened to limit its opening movement and hold the other adjacent valve closed.

9. In a valve mechanism for indicating the water level in steam boilers, the combination 55 of an upright water column; and a plurality of gauge cocks mounted on said column one above another, each cock comprising a valve and a lever for actuating it and the several actuating levers being identical and formed 60 and arranged so that the levers of valves adjacent to each other mutually engage when one valve is opened to hold the other adjacent valve closed.

10. As a new article of manufacture, a 65 valve actuating member for gauge cocks, said

member having stop devices so formed that when a plurality of said members are mounted upon a corresponding number of gauge cocks of a water column one stop device of each member when the latter is moved to open 70 its valve will engage a stop device of an adjacent member to hold its valve in closed position.

In testimony whereof, I hereunto affix my 75 signature.

GEORGE W. OSBORN.
